United States Patent Office

Des. 181,981
Patented Jan. 28, 1958

181,981

PEN-HOLDER

Charles L. Ingersoll, Wheaton, Ill.

Application May 9, 1957, Serial No. 46,079

Term of patent 14 years

(Cl. D74—1)

The dotted line illustration of the pen shown in Figure 1 is for illustrative purposes only.

I claim:

The ornamental design for a pen-holder, substantially as shown and described.
